LEDGER CLAMP

Filed Dec. 13, 1928

UNITED STATES PATENT OFFICE

THOMAS H. KINGSTON, OF WEST SOMERVILLE, MASSACHUSETTS, ASSIGNOR TO BUILDERS' PATENT SCAFFOLDING COMPANY, A PARTNERSHIP COMPOSED OF FRANK G. KINGSTON, A. R. KINGSTON, C. C. PIMM, AND MABEL G. KITCHEN, DOING BUSINESS AT WEST SOMERVILLE, MASSACHUSETTS

LEDGER CLAMP

Application filed December 13, 1928. Serial No. 325,778.

This invention relates to builders' scaffoldings and in particular to clamps for securing the ledger boards to the poles, the ledger boards being the horizontal boards placed 5 edgewise vertically, for the support of the flooring of the scaffolding. These clamps are of great importance because upon the security of their hold depends the safety of persons and lives of human beings. Consistent 10 with their importance, they should be capable of easy and quick application and removal in the interest of diminishing as much as possible the cost of erection and taking down the scaffolding. Accordingly, an important 15 object of the invention is to provide a construction of clamp which will combine the properties of complete security and easy and rapid installation and removal.

The invention consists in whatever is described by or is included within the terms or scope of the appended claims.

In the drawing:—

Fig. 1 is a perspective view of a portion of scaffolding showing the application of a ledger board clamp embodying my invention.

Fig. 2 is a vertical section thereof;

Fig. 3 is a horizontal section on the line 3—3 of Fig. 2;

Fig. 4 is a view in side elevation of another embodiment of the invention;

Fig. 5 is a perspective fragmentary view of still another embodiment of the invention;

Fig. 6 is a perspective fragmentary view of another embodiment of my invention.

The several embodiments of my invention shown in the drawing are found in constructions which include what, for convenience 40 will be termed a main or body member in the form of a bar that, when applied to the scaffolding, extends vertically across the outer face of the pole, and two hook-form jaws pivoted to said body at the upper and lower ends thereof, and adapted to reach across or straddle the ledger board and hook over or overlap the ledger board at the top and bottom edges respectively, and a screw applied at the vertical center of the body for 45 exerting clamping pressure against the outer

side of the pole. Ledger board clamps are applied to a single thickness of board and also at times to a double thickness as when the ends of adjoining ledger boards overlap at the pole, and a feature of the invention 55 is the quick and easy adaptation of the clamp to single or double thicknesses of ledger boards without dependence upon adjustment of the clamp screw.

The body member, 10, is made of a length 60 or piece of channel iron, the web of the channel being cut away at top and bottom and the side flanges bent or brought towards each other and extended parallel sufficiently close together to provide for the snug fitting between them of the end of the upper or lower jaw, 11, as the case may be, such jaw being pivotally held as by means of a pin or rivet 12, passing through alining holes in the side 65 plates and the jaw end.

The lower jaw, although free to swing upward towards the body member, is limited so that it will not swing below a horizontal or substantially horizontal position, and a stop device of some sort is provided which will prevent it moving below the horizontal position or one at right angles to the body member. Such stop may be simply a lug, 13, projecting from its bottom edge which will encounter the adjacent inner edge of the body 75 member. Thus, when the workman is applying the clamp to the scaffolding the lower bar when swung down to horizontal position is in its proper position to have its inner or hooked end engage the ledger board and the workman thus does not have the inconvenient 80 job of swinging it to and holding it in such horizontal position. The upper jaw has no such stop device, but is free to swing through a large range and, of course, when the clamp is placed in position with the lower bar extending beneath the ledger board, it is a simple act for the workman to swing the top bar over, above the top edge of the ledger board, 85 allowing it to drop into its proper position with its inner hooked end overlapping the inner side of the ledger board at the top.

As it is desirable to have the channel made of as light metal as possible, I provide a reinforcing bar or strip, 14, of metal which is 90

riveted to the channel web preferably on the inner side at the central portion thereof longitudinally, and such reinforcing bar or strip has a central hole that alines with a hole in said web, both holes being threaded for the clamp screw, 15. Thus the reinforcing bar provides extra material to give an extended engagement between the clamp screw and the body member. Thus reinforced, the channel 10 is given all needed strength to resist tendency to buckle under the pressure exerted thereagainst when the clamp screw engages at its inner end the outer side of the scaffolding pole. At the inner end of the clamp screw, 15, is swiveled a pole engaging plate, 16, of substantially larger area than the end of the screw so as to reduce the unit pressure on the pole. Said plate, 16, is no wider than the distance between the channel flanges, so that 20 it may be placed within the channel and thereby protected from damage.

As has already been indicated, overlapped or spliced ledger boards present a double thickness for engagement by the clamp. To 25 take care of the difference in thickness between a single ledger board and two ledger boards, manipulation of the screw would be a tedious, slow operation. I, therefore, provide in certain embodiments of my invention 30 the jaws with means which will enable the jaws to deal with either a single thickness of ledger boards or a double thickness. As shown in Figs. 1 and 2, this means may take the form of a two-part jaw which is adjust- 35 able as to length so that the hooked end may be placed further from or nearer to the body member. Each jaw in this case, consists of two overlapping shanks, one pivoted to the body member and the other carrying the hook 40 member slidably longitudinally one upon the other. One shank has a longitudinally ex- 45 tends slot, 17, from which extend several, L-shaped slots, 18, as shown in Fig. 2, and the other shank has two headed pins, 19, that are spaced apart a distance corresponding to the 50 distance between two adjoining slots, 18, so that by moving the shank carrying the pins to play back and forth in the slots, it may be shifted to place the jaw into either of the two desired positions in which it will be firmly held under the clamping pressure.

As shown in Fig. 4, instead of a single hook adjustable to different positions, there may be two hooks adapted for alternate use. 55 These may be two jaws, 20, of different length both secured by the same pivot, 120, to the body member, 100, as shown. With the pivoted two-jaw arrangement, the short jaws not in use are swung out of the way, but not 60 the long jaws when the short are used. The parts designated, respectively, 130, 150 and 160 in Fig. 4 are similar to the parts designated, respectively, 13, 15 and 16 in Fig. 1.

As shown in Fig. 5, the jaw, 110, has but 65 one hook.

Besides the advantages mentioned of the pivotal connection between the jaws and the body member, there is the further advantage of folding or collapsing the clamp into a compact space for storage or handling.

Of course, other clamping means than a screw may be employed. For example, a cam arrangement may be used as shown in Fig. 6, where a cam or eccentric, 21, is mounted on a pivot pin, 22, journaled in the side flanges of the member, 10, with a handle, 23, that projects through a vertical slot in the web for easy manipulation. The cam or eccentric, 21, may bear directly upon the outer side of the pole, or as shown in Fig. 6, it may engage the end of a shank, 24, of a pole-engaging plate or shoe, 25, the shank, 24, being supported and guided by a hole in a cross bar or strap, 26, riveted to the side flanges of the member, 10.

The channel for the body thus is specially advantageous for use of the cam clamp as it enables the latter readily to be mounted thereon and as the reaction pressure falls on the side flanges edgewise, and on both, ample resistance to buckling is had.

What I claim is:—

1. A ledger board clamp having jaw means and a body member consisting of a channel having a web and flanges, a reinforcing plate at midlength of the channel and a clamp screw, said plate and web having alined threaded holes through which said screw passes, the flanges of the channel at opposite ends being bent towards each other and said jaw means having shanks pivoted between such ends.

2. A ledger board clamp comprising a body member, jaws and clamping means applied to the body member, said body member consisting of a channel having side flanges bent at their ends towards each other and means attaching the jaws to said bent ends.

3. A ledger board clamp having a vertically extending body and jaw members pivoted to the body, at vertically spaced apart points, at least one of the jaw members being limited to swing between a substantially horizontal position and a vertical position, and coacting parts on said body and the jaw member which is limited to swing between a substantially horizontal position and a vertical position that contact when said jaw member is in a substantially horizontal position, the jaw portions of the jaw members extending vertically when in ledger board clamping position.

In testimony whereof I hereunto affix my signature,

THOMAS H. KINGSTON.
